UNITED STATES PATENT OFFICE.

HEINRICH DEGENER, OF BERLIN, GERMANY, ASSIGNOR TO MERGENTHALER LINE-
TYPE COMPANY, A CORPORATION OF NEW YORK.

LINE SETTING AND CASTING MACHINE.

1,069,927.

Specification of Letters Patent. Patented Aug. 12, 1913.

original application filed August 22, 1910, Serial No. 578,459. Divided and this application filed June 8, 1911. Serial No. 632,908.

To all whom it may concern:

Be it known that I, HEINRICH DEGENER, residing at 26 Hollmannstrasse, Berlin, Germany, a subject of the King of Prussia, German Emperor, manager, having invented certain new and useful Improvements in or Relating to Line Setting and Casting Machines, do hereby declare that the following is an exact specification of the same, being a division of an application filed by me on the 22d day of August, 1910, Serial No. 578,459.

This invention relates to improvements in line setting and casting machines of the known Mergenthaler type, and has particular reference to the fixing or locking of the matrix line in the casting carriage.

The accompanying drawings show by way of example constructions according to this invention.

Figure 1 shows a front elevation of the locking jaw, partly in section, Fig. 2 the corresponding plan, Fig. 3 a section through Fig. 1 on line A—A, and Fig. 4 a section through Fig. 1 on line B—B. Figs. 5—11 show a device on the locking device for the line, intended, when a line is not fully set, to prevent the foremost matrix from turning during the transfer of the matrix line to the elevator and from causing disturbances, namely Figs. 5 and 6 show one construction in elevation and plan, while Fig. 7 is an elevation of a second construction. Figs. 8 and 9 show a device in which the springy jaw can be locked in its back position by hand, in case the casting of the line is to be repeated, Fig. 8 being an elevation and Fig. 9 a plan. Figs. 10—11 show another construction by which the springy member is automatically operated or locked, Fig. 10 showing the position after the introduction of the line between the locking jaws, and Fig. 11 shortly before the introduction of the line in case of multiple casting.

For locking the line set, for the purpose of carrying it farther to the casting device, is used, as is well known, a device in which the line consisting of matrices and spacers, is gripped between two jaws which must be arranged in an adjustable manner for the purpose on the one hand of enabling the length of the line to be altered, and on the other hand, for allowing, during the justifying, a small widening in order to insure better driving in of the spacer wedges.

It is already known to arrange one and the same means for these two adjustments, namely a screw secured to the frame of the machine, while in the adjustable jaw is mounted the corresponding nut. That device has, however, the disadvantage that in adjusting the line, it is necessary to disconnect the screw from the justifying mechanism which disconnection is a complicated matter. It has been attempted to remedy the disadvantage by inserting between the nut arranged in the jaw, and the jaw itself, an adjustable connection which was used for setting the different lengths of line, and by leaving to the screw spindle only the adjustment for the purpose of justifying. This arrangement occupies, however, too much space, and also increases the number of adjustable parts on the machine.

The locking device according to this invention (Figs. 1—4) is a device which goes back to the joint operation of the two adjustments by means of one part, but on the other hand affords means for avoiding the above mentioned difficulties combined therewith. The spindle 19 used for the adjustment is mounted with its front end 20 in the adjustable jaw in a rotatable but not longitudinally movable manner. The adjustable jaw is shown in the drawing consisting of two parts, 21 and 22, the latter one of which rests against a stop arranged in the former. This division of the locking jaw has nothing to do with the invention itself, but has been made only for the purpose of enabling the vise jaw to be moved entirely to the right when there are no matrices in the line, and only reglets are cast. In the frame of the machine 23 is mounted the nut belonging to the spindle and consisting of two parts 24 and 25. Between the two parts of the nut engages the front end of the spindle 26 flattened on both sides and thus forming a cutting edge, which can be rotated by means of a handle 27. By rotating the spindle in question, the two parts 24 and 25 of the nut are moved outward away from the spindle 19, so that they release the latter, and the spindle becomes longitudinally adjustable. The springs 28, after the turning back of the handle 27, bring the nut again into engagement with the spindle. The spindle itself is preferably provided with a division in accordance with type body dimensions, preferably with a pitch of $\frac{1}{2}$ cicero.

The spindle is provided with a slot 29 extending throughout the whole of its length and engaging with a key 30 connecting the spindle to the bush 31. The spindle is consequently adjustable but not rotatable relatively to the bush 31. The bush 31 is mounted in a slotted crank 32 composing opposed movable clamping jaws 36 and 37 which can be fixed by tightening a set-screw 33. The 5 crank 32 is operated in the well known manner by means of the rod 34 and the spring 35, from the justifying mechanism.

The working of the device is as follows: Before or after the justifying, the crank 32 10 effects in well known manner a reciprocation and being secured to the bush 31, rotates with the latter the spindle 19 to and fro. The spindle, and with it the locking jaw, is consequently slightly moved to and fro as 15 the nut is in engagement with the spindle. If it is necessary to adjust for another length of line, this is effected—when it is a question of an adjustment, as is generally the case, to the extent of complete or $\frac{1}{2}$ cicero units—by turning the handle 27, 20 whereby the two parts of the nut are moved away from each other, whereupon the spindle is moved to the right or to the left to the extent of a corresponding number of threads. Only when it is necessary to adjust to the extent of smaller units than $\frac{1}{2}$ cicero, it is necessary to release the setting screw 33 and to effect the adjustment by 25 manually turning the spindle. The bush 31 participates in the rotation of the spindle, 30 and is afterward fixed again in the crank 32 by tightening the set screw 33. When the line is not set completely full, there is between the matrix at the farthest left hand 35 end, and the adjustable locking jaw such a great clearance that the matrix in question can easily turn and cause trouble. In order to remedy the drawback in question, a spring member can be pushed in, which always 40 comes to lie close against the left hand matrix and prevents it from turning over.

In the construction shown in Figs. 5-7, the adjustable jaw 22 which rests in well known manner against the stop 29, is slotted 45 in the center. Into the said slot is introduced an adjustable part 312 pressed forward by a spring 313, the movement of the part being limited by a pin 314. In the pushed in position, the insertion 312 is flush in front with the adjustable jaw. Before the 50 line arrives, the part 312 is in the position shown dotted in Figs. 5-7. The matrix line 315 is then moved in well known manner between the two grippers to the casting 55 point, and the left hand gripper 316 strikes during that movement with its point a projection or stop 317 of the part 312 and pushes the latter in as far as required by the length 60 of the line just set. When the matrix line 65 is carried downward between the jaws, it

will always rest on the left hand side close against the part 312, so that a turning of the first matrices is prevented. During the subsequent justifying of the line, the spring 313 which is only a weak one, is compressed to such an extent that the front edge of the part 312 is flush with the front edge of the jaw. The part 312 in the position of rest projects from the jaw to such an extent that it remains operative even in case of the loosest line. The arrangement in Fig. 7 is very similar, only in this case the whole jaw 22 is mounted in an adjustable manner. In order to insure greater mobility, it can be preferably mounted on rollers or balls 70 75 80 85 90 95 100 105 110 115 120 125 130

In making repeated castings, the construction shown in Figs. 5-7 would have the disadvantage that when the line in the casting carriage from its uppermost position is brought for the second time between the locking jaws, it would come to rest on the upper edge of the part of the locking jaw, advanced by the spring, as the finger which otherwise adjusts the spring member to the proper width, is no longer present in this case, but has been already moved back to its original position for receiving a new line. Below are given two methods for remedying the disadvantage in question and for locking the spring jaw part in its rear position.

In the first construction shown in Figs. 8 and 9, the locking jaw 22 is itself exactly the same as in the construction shown in Figs. 5 and 6. In this case as well, the central part 312 is adjustable and is pushed forward by the spring 313, a pin 314 being provided for limiting the travel, and guided in an elongated hole in the stationary part of the jaw. There is here further provided a spring 336 with a button 334 for seizing it, and with a locking tooth 335 on the bottom surface. If the movable or adjustable part 312 is moved in the usual manner by the matrix line, that is to say, to such an extent that its front surface is flush with the front surface of the two lateral stationary parts, the locking tooth does not act as it does not yet come into engagement, on the contrary, the part 312 again springs forward after the removal of the line. If, however, the line is to be cast repeatedly, the compositor presses the part 312 somewhat farther into the slot between the two lateral parts. In that case, the locking tooth 335 springs behind the part 314 as shown in Fig. 8, and thus locks the part 312 in its back position. The matrix line 315 can then be brought into its bottom position without the part 312 disturbing and coming into its path. When this line is distributed and a new line 130

set, the compositor, by raising the button 334, releases again the spring device, and the setting is continued in the ordinary manner.

- 5 In the construction shown in Figs. 10 and 11, hand locking becomes superfluous, nevertheless the path for the line always remains free, as the spring member is pressed against the matrix line only when the latter is all 70
 10 ready between the locking jaws. In the position of rest, the locking jaw 22 is in the position shown in Fig. 11. The spring member 312 is carried by a bolt 337 provided at its end with a collar or with a nut 338. A 15 spring 339 which on one side rests against the jaw, and on the other side against the collar draws the spring part 312 in the position of rest into the jaw always to such an extent that its front surface is flush with 20 the front surface of the jaw, that is to say, does not project into the path of the matrix line. Behind the bolt 337, in the same recess, is arranged a spring 340 which is stronger than the spring 339, and the other 25 side of the spring 340 rests against a bolt 341 prevented from turning by a pin 342 guided in a slot of the locking jaw 22, which pin limits at the same time the travel of the bolt in question. The rear end of the bolt 30 341 is beveled. The first elevator or casting carriage 343 which receives the matrix line from the collector and carries it to the casting or distributing place, is provided with a projection 344 with a bevel corresponding 35 to the bevel of the bolt 341. When the casting carriage is lowered in order to bring the matrices into the casting position, the projection 344 engages with the bolt 341 and forces the latter into the position shown in 40 Fig. 10 into the locking jaw. The spring part 312 is then moved into the path of the matrix line, the spring 339 being at the same time compressed, namely at the moment when the matrix line is already partly 45 between the locking jaws. The spring part engages then with the matrices standing on the farthest left hand end, the spring 340 being compressed to a greater or less extent according to the width of the matrix line. 50 The justifying then takes place, and the spring part is again forced completely into the longer jaw owing to the widening of the matrix line. When the matrix line is moved after the casting into the distributing position, the spring part remains in the locking 55 jaw owing to the removing of the stop 344 from the bolt 341, and at a repeated descent of the casting carriage for the purpose of a new casting, the line, without finding any 60 obstacle, can enter between the two locking jaws. In Fig. 10 is further shown dotted line coming from the collector elevator, and subsequently received by the casting carriage. The locking jaw 22 is provided 65 at its back end with an oblique slot with

which engages the projection or stop 344, so that the slide of the locking jaw facing the casting mold, retains its solid surface so that it could cover completely the casting slot if necessary.

Having now particularly described and ascertained the nature of my invention and in what manner the same is to be performed, I declare that what I claim is:

1. In a typographical machine comprising casting mechanism, the combination of the locking jaw, the rotatable screw threaded spindle coöperating therewith, and a stationary abutment nut engaging the spindle, the said nut being formed in sections to permit of its ready adjustment with reference to the spindle. 75

2. In a typographical machine comprising casting mechanism, the combination of the locking jaw, the rotatable screw threaded spindle coöperating therewith, and a stationary abutment nut engaging the spindle, the said nut being formed in sections to permit of its ready adjustment with reference to the spindle, together with means to rotate 85 the spindle. 90

3. In a typographical machine comprising casting mechanism, the combination of the locking jaw, the rotatable screw - threaded spindle coöperating therewith, an abutment 95 therefor, and a device for rotating said spindle, the said device being constructed to permit the longitudinal movement of the spindle in relation thereto.

4. In a typographical machine comprising casting mechanism, the combination of the locking jaw, the rotatable screw threaded spindle coöperating therewith, an abutment therefor, and a device for rotating the spindle, the said device being provided with a 105 key to engage the spindle to permit its relative longitudinal movement. 100

5. In a typographical machine comprising casting mechanism, the combination of the locking jaw, the rotatable screw threaded spindle coöperating therewith, an abutment 110 therefor, and a device for rotating the spindle, the said device comprising clamping jaws embracing the spindle and movable toward and from each other to permit its ready engagement with and disengagement 115 from the spindle.

6. In a typographical machine comprising casting mechanism, the combination of the locking jaw, the rotatable screw threaded 120 spindle coöperating therewith, an abutment therefor, and a device for rotating the spindle, the said device comprising a clamp to permit its ready engagement with and disengagement from the spindle, and provided 125 with a key to engage the spindle and permit its relative longitudinal movement.

7. In a typographical machine comprising casting mechanism, the combination of the locking jaw, the rotatable screw threaded 130

spindle coöperating therewith, and a stationary abutment nut engaging the spindle, the said nut being formed in sections to permit of its ready adjustment with reference 5 to the spindle, and provided with means to shift the said sections into and out of operative relation to the spindle.

8. In a matrix setting and line casting machine in combination a locking jaw confining the length of the line and being moved in setting the length of the line and in justifying, a screw spindle for adjusting the said locking jaw, a nut mounted in the frame and adapted to be brought quickly in or out of engagement with the screw spindle, a bush connected to the spindle in a slidable manner by a key and a clamp connection between the bush and the justifying part.

9. In a matrix setting and line casting machine in combination a locking device for the matrix line containing a locking jaw, a spring part resting against the left hand side of the matrix line, said spring part being mounted in the said locking jaw, and 25 an elevator or casting carriage transporting the matrix line to the casting and distributing position, said elevator pressing the spring part into the path of the matrix line during its descent.

30 10. In a matrix setting and line casting machine in combination a locking device for the matrix line containing a locking jaw, a spring part resting against the left hand side of the matrix line, said spring part being mounted in the said locking jaw, a spring holding the spring part in the normal position within the locking jaw and an elevator or casting carriage transporting the matrix line to the casting and distributing 40 position, said elevator pressing the spring part into the path of the matrix line during its descent.

11. In a matrix setting and line casting machine in combination a locking device for the matrix line containing a locking jaw, a spring part resting against the left hand side of the matrix line, said spring part being mounted in the said locking jaw, a spring holding the spring part in the normal 45 position within the locking jaw, a second spring and an elevator or casting carriage transporting the matrix line to the casting and distributing position, said elevator tensioning the said second spring during its descent and moving the said spring part in a springy manner in the path of the matrix line.

12. In a matrix setting and line casting machine in combination a locking device 60 for the matrix line containing a locking jaw, a spring part resting against the left hand side of the matrix line, said spring part being mounted in the said locking jaw, a

spring holding the spring part in the normal position within the locking jaw, a second spring, a bolt mounted in the locking jaw and an elevator or casting carriage transporting the matrix line to the casting and distributing position, said elevator engaging the bolt during its descent thereby 65 tensioning the said second spring and moving the said spring part in a springy manner in the path of the matrix line.

13. In a matrix setting and line casting machine in combination a locking device for 75 the matrix line, containing a locking jaw, a spring part resting against the left hand side of the matrix line, said spring part being mounted in the said locking jaw, a spring holding the spring part in the normal 80 position within the locking jaw, a second spring, a bolt mounted in the locking jaw and having a beveled surface, an elevator or casting carriage transporting the matrix line to the casting and distributing position 85 and a projection arranged on the elevator and having a bevel portion, said projection engaging the bolt during the descent of the elevator thereby tensioning the said second spring and moving the matrix line.

14. In a typographical machine comprising casting mechanism, the combination of the confining jaw provided with a yielding part to contact with the matrix line, and the first elevator having a member arranged to 95 move the yielding part into the path of the line.

15. In a typographical machine comprising casting mechanism, the combination of the confining jaw provided with a relatively 100 movable yielding part to contact with the matrix line, and additional means arranged to move the yielding part relatively to the jaw and into the path of the line.

16. In a typographical machine comprising casting mechanism, the combination of the confining jaw provided with a yielding part to contact with the matrix line, and means for presenting the line thereto, the said presenting means having a member arranged to move the yielding part into the path of the line.

17. In a typographical machine comprising casting mechanism, the combination of the confining jaw provided with a movable 115 part to contact with the matrix line, means for presenting the line thereto, and intermediate resilient devices, said presenting means yieldingly moving the contacting part into the path of the line.

In witness whereof I hereunder set my hand in the presence of two witnesses.

HEINRICH DEGENER.
